UNITED STATES PATENT OFFICE.

LUTHER L. KNOX, OF NILES, OHIO, ASSIGNOR TO KEYSTONE BRONZE COMPANY, OF PITTSBURGH, PENNSYLVANIA, A CORPORATION OF PENNSYLVANIA.

BOSH-PLATE FOR BLAST-FURNACES AND THE LIKE.

1,101,700.

Specification of Letters Patent. Patented June 30, 1914.

Application filed August 4, 1911. Serial No. 642,336.

To all whom it may concern:

Be it known that I, LUTHER L. KNOX, of Niles, in the county of Trumbull and State of Ohio, have invented a new and useful Improvement in Bosh-Plates for Blast-Furnaces and the like, of which the following is a full, clear, and exact description, reference being had to the accompanying drawings, forming part of this specification, in which—

10 Figure 1 is a vertical section of a portion of the bosh and stack wall of a blast furnace, showing a number of my improved cooling plates applied thereto. Fig. 2 is an end view of one of the plates. Fig. 3 is a horizontal longitudinal section of the same. Fig. 4 is a vertical longitudinal section. Fig. 5 is a detail view of a portion of the spray pipe, and Fig. 6 is a similar view showing a modification of the spray pipe.

20 My invention has relation to bosh plates for blast furnaces and the like, and is designed to provide a bosh plate having means of improved and more effective character for introducing the cooling water thereto, and providing for an effective circulation of such water therein.

Referring to the accompanying drawings, in which I have shown the preferred embodiment of my invention, the numeral 2 designates a hollow bosh plate which is preferably formed with a lateral and also a vertical taper toward its inner end, so that it is of less depth at its inner than at its outer end. The top 3 of the plate is also preferably arched transversely. The hollow interior of the plate forms a chamber for a cooling liquid which is introduced therein by means of a pipe 4, which extends inwardly through the outer end wall 5 along one side of the interior chamber to a point near the inner end thereof, where it is bent to form a transversely extending arm 6. This arm 6 is provided with means for discharging water against the inner end wall 7 of the plate, such as the series of openings

8, shown in Figs. 3 and 5 or the series of slots 9, shown in Fig. 6. The free end of the discharge arm 6 of the water pipe may be closed in any suitable manner, as by a plug 10. The outer end of the pipe 4 is provided with suitable means for its connection to a supply pipe 11. The water discharged from the transverse arm 6 of the water pipe impinges directly against the inner end wall 7 of the plate where its cooling action is most effective. The heated water rises to the upper portion of the plate and escapes through the outlet connection 12, which preferably communicates with the highest point of the chamber. A blow- pipe or clean out connection 13 may also be provided.

The bosh plate may be conveniently formed of plates or sheets of metal welded together, the water pipe being placed between the plates or sheets before they are welded.

14 designates vertical stay bolts for bracing and swinging the structure.

I claim:

A bosh plate for blast furnaces, comprising a hollow sheet metal segmental body having a pipe extending therein from the outer end thereof, the pipe entering said member adjacent to one of its side edges and extending inwardly to a point near the end wall thereof, the transverse arm of the pipe having a plurality of discharge openings therein, the upper surface of the member being convex and there being a central discharge opening at its outer end at substantially the highest point thereof, substantially as described.

In testimony whereof, I have hereunto set my hand.

LUTHER L. KNOX.
